The ornamental design for a flower pot cover, as shown and described.

DESCRIPTION

FIG. 1 is a perspective view of our new flower pot cover design;

FIG. 2 is a side elevational view thereof;

FIG. 3 is a top plan view thereof;

FIG. 4 is a bottom plan view thereof;

FIG. 5 is a side elevational view of the design of FIG. 1, the only difference being in the horizontal angle of the skirt; FIG. 6 is a side elevational view of the design of FIG. 1, the only difference being in the near vertical angle of the skirt; FIG. 7 is a side elevational view of the design of FIG. 1, the only difference being in the downward angle of the skirt;

FIG. 8 is a side elevational view of a second embodiment of the design of FIG. 1, the only difference being in the placement of the cutouts in the base;

FIG. 9 is a side elevational view of a third embodiment of the design of FIG. 1, the only difference being in the placement of the cutouts in the base;

FIG. 10 is a side elevational view of a fourth embodiment of the design of FIG. 1, the only difference being in the placement of the cutouts in the base;

FIG. 11 is a perspective view of a fifth embodiment of our new flower pot cover design;
FIG. 12 is a side elevational view thereof;
FIG. 13 is a top plan view thereof;
FIG. 14 is a bottom plan view thereof;
FIG. 15 is a side elevational view of the design of FIG. 11, the only difference being in the horizontal angle of the skirt;
FIG. 16 is a side elevational view of the design of FIG. 11, the only difference being in the near vertical angle of the skirt;
FIG. 17 is a side elevational view of the design of FIG. 11, the only difference being in the downward angle of the skirt;
FIG. 18 is a side elevational view of a sixth embodiment of the design of FIG. 11, the only difference being in the placement of the cutouts in the base;
FIG. 19 is a side elevational view of a seventh embodiment of the design of FIG. 11, the only difference being in the placement of the cutouts in the base;
FIG. 20 is a side elevational view of an eighth embodiment of the design of FIG. 11, the only difference being in the placement of the cutouts in the base;
FIG. 21 is a perspective view of a ninth embodiment of our new flower pot cover design;
FIG. 22 is a side elevational view thereof;
FIG. 23 is a top plan view thereof;
FIG. 24 is a bottom plan view thereof;
FIG. 25 is a side elevational view of the design of FIG. 21, the only difference being in the horizontal angle of the skirt;
FIG. 26 is a side elevational view of the design of FIG. 21, the only difference being in the near vertical angle of the skirt;
FIG. 27 is a side elevational view of the design of FIG. 21, the only difference being in the downward angle of the skirt;
FIG. 28 is a side elevational view of a tenth embodiment of the design of FIG. 21, the only difference being in the placement of the cutouts in the base;
FIG. 29 is a side elevational view of an eleventh embodiment of the design of FIG. 21, the only difference being in the placement of the cutouts in the base;
FIG. 30 is a side elevational view of a twelfth embodiment of the design of FIG. 21, the only difference being in the placement of the cutouts in the base;
FIG. 31 is a perspective view of a thirteenth embodiment of our new flower pot cover design;
FIG. 32 is a side elevational view thereof;
FIG. 33 is a top plan view thereof;

FIG. 34 is a bottom plan view thereof;
FIG. 35 is a side elevational view of the design of FIG. 31, the only difference being in the horizontal angle of the skirt;
FIG. 36 is a side elevational view of the design of FIG. 31, the only difference being in the near vertical angle of the skirt;
FIG. 37 is a side elevational view of the design of FIG. 31, the only difference being in the downward angle of the skirt;
FIG. 38 is a side elevational view of a fourteenth embodiment of the design of FIG. 31, the only difference being in the placement of the cutouts in the base;
FIG. 39 is a side elevational view of a fifteenth embodiment of the design of FIG. 31, the only difference being in the placement of the cutouts in the base;
FIG. 40 is a side elevational view of a sixteenth embodiment of the design of FIG. 31, the only difference being in the placement of the cutouts in the base;
FIG. 41 is a perspective view of a seventeenth embodiment of our new flower pot cover design;
FIG. 42 is a side elevational view thereof;
FIG. 43 is a top plan view thereof;
FIG. 44 is a bottom plan view thereof;
FIG. 45 is a side elevational view of the design of FIG. 41, the only difference being in the horizontal angle of the skirt;
FIG. 46 is a side elevational view of the design of FIG. 41, the only difference being in the near vertical angle of the skirt;
FIG. 47 is a side elevational view of the design of FIG. 41, the only difference being in the downward angle of the skirt;
FIG. 48 is a side elevational view of an eighteenth embodiment of the design of FIG. 41, the only difference being in the placement of the cutouts in the base;
FIG. 49 is a side elevational view of a nineteenth embodiment of the design of FIG. 41, the only difference being in the placement of the cutouts in the base; and,
FIG. 50 is a side elevational view of a twentieth embodiment of the design of FIG. 41, the only difference being in the placement of the cutouts in the base.
The characteristic feature of the design resides in the specific pleating arrangement, comprised of the parallel disposition of the exterior folds, in combination with the interior V-shaped folds, all as best seen in FIGS. 1, 11, 21, 31 and 41. The flower pot cover has no substantial thickness.
